(57) **ABSTRACT**

A new distinct variety of grapevine named 'ARDTHIRTYFIVE' abundantly forms attractive crunchy seedless berries with a red skin coloration; medium density in large clusters which display a naturally sweet flavor, commonly ready for harvesting during July in San Joaquin Valley of Central Calif., U.S.A, and displays good eating qualities as a table grape. The fruit firmness renders the fruit well amenable for handling, shipping, and storage.

1 Drawing Sheet

1

Classification: The present invention relates to a new *Vitis vinifera* Grapevine.

Variety denomination: The new Grapevine has a varietal denomination 'ARDTHIRTYFIVE'.

BACKGROUND OF THE INVENTION

A breeding program was initiated during the late 1990's near Bakersfield in San Joaquin Valley of Central Calif. In 2013, during this breeding program, a new variety of *Vitis vinifera* was created by deliberate cross breeding of two parent plants by emasculation of the pollen bearing organ of the female and introducing pollen from another male origin. The female parent of the new variety was 10-10+2, which is a very fertile and crispy seedless white table grape variety (non-patented in the United States). The male parent (i.e. the pollen parent) of the new variety was 25-51+2, a naturally sweet and crisp seedless red variety (non-patented in the United States).

2

The parentage of the new variety can be summarized as follows:

10-10+2 X 25-51+2

5 An artificial pollination was created, and the result was an embryo which possessed unique genetic qualities. The rudiments resulting from the above pollination were embryo rescued. In 2014 the plant was transplanted to Bakersfield in San Joaquin Valley of Central Calif.

10 It was found that the new grapevine of the present invention possesses the following combination of characteristics:

15 (a) Forms attractive crunchy seedless berries with a red skin coloration; in medium density, large clusters which display a naturally sweet flavor,

(b) Commonly bears fruit during the month of July in the San Joaquin Valley of Central California, U.S.A., and

(c) Bears fruit that is firm and is well amenable for storage, handling, and shipping.

20 (d) Produces 40 bunches per vine, and an average of about 1-2 bunches per shoot, at a total of 48 lbs fruit per vine.

The new variety during observation to date has displayed no visible disease, and has displayed an ability to well resist cold, drought, heat; but sensitive to direct exposure to sun and wind. The fruit of the new variety has been found to display excellent handling and shipping qualities combined with desirable dessert eating qualities.

25 The new variety of the present invention has been found to undergo asexual propagation beginning in 2015 near Bakersfield in the San Joaquin Valley of Central Calif., U.S.A. by bud grafting on mature Thompson rootstock (non-patented in the United States). Such asexual propagation has been conducted thereafter in successive years to date and has shown that the characteristics of the new variety

TABLE 1

ARDTHIRTYFIVE compared with parents & closely related variety:				
	ARDTHIRTY- FIVE	10-10+2 (Maternal)	25-51+2 (Paternal)	Flame (unpatented in the United States)
Berry shape	Broad ellipsoid	Cylindrical	Broad ellipsoid	Globose
Berry color	Red	White	Red	Greyish red
Bunch density	Lax	Medium	Medium	Tight

are strictly transmissible from one generation to another. Accordingly, the new variety undergoes asexual propagation in a true to type manner.

SUMMARY OF THE INVENTION

The new variety ARDTHIRTYFIVE is a red seedless table grape with a high production, e.g., about 40 bunches per vine, and an average of about 1-2 bunches per shoot.

Asexual reproduction by micro propagation of the new variety as performed near Bakersfield, Calif., U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

The drawing shows leaves, stems and grapes of ARDTHIRTYFIVE.

DETAILED BOTANICAL DESCRIPTION

The chart used in the identification of colors is The R.H.S. Colour Chart of The ROYAL HORTICULTURAL SOCIETY (3rd Edition). The description is based on the observation of plants growing on 'Thompson Seedless' rootstock outdoors near San Joaquin Valley of Central California, 35 U.S.A.

VINE CHARACTERISTICS:

vigor	Vigorous upright shoots
productive capacity	Bearing at a natural, average capacity. Spur pruning.
trunk	Strong and developed. Diameter is 3.3 inches, measured at 5.2 inches above ground. Rough with a fibrous, shaggy exterior. Light maple brown coloring (greyed orange 177C)

Date of bud burst in Bakersfield Calif.: February 24th.

YOUNG SHOOT CHARACTERISTICS:

Openness of tip	wide open
Density of prostrate hairs on tip	absent or very sparse
Anthocyanin coloration of prostrate hairs on tip	none (yellow green 144A)

YOUNG LEAF CHARACTERISTICS:

Color of upper side of blade	yellow green 144A
Color of lower side of blade	yellow green 144B
Density of erect hairs between main veins on upper side of blade	sparse

-continued

YOUNG LEAF CHARACTERISTICS:

5	Density of erect hairs between main veins on lower side of blade	sparse
	Density of prostrate hairs on main veins on upper side of blade	sparse
	Density of prostrate hairs on main veins on lower side of blade	sparse

SHOOT CHARACTERISTICS:

15	Attitude (before tying)	semi-erect
	Color of dorsal side of internodes	yellow green 144B
	Color of ventral side of internodes	yellow green 152B
	Color of dorsal side of nodes	yellow green 145A
	Color of ventral side of nodes	yellow green 151A
	Density of erect hairs on internodes	absent or very sparse
	Density of prostrate hairs on internodes	sparse
20	Length of tendrils	3.5 inches
	Diameter of tendrils	0.04 inches
	Color of tendrils	yellow green 153A
	Number of tendrils at bloom	3
	Positioning of first flowering and fruiting node	the first bunch is in the 3 rd node
25	Inflorescence number per flowering shoot	1-2

FLOWER CHARACTERISTICS:

30	Reproductive organs	fully developed stamens and fully developed gynoecium
	Flower length	0.3 inches
	Flower diameter	0.15 inches
	Pistil length	0.1 inches
	Pistil color	green 143B
	Pollen Amount	poor
	Pollen color	yellow 6A
	Stamen color	yellow green 144A
40	Stamen length	0.1 inches
	Number of stamen	5

First bloom in Bakersfield, Calif.: May 1st.

Date of full bloom in Bakersfield, Calif.: May 9th.

MATURE LEAF CHARACTERISTICS:

50	Size of blade	5.5 x 5.5 inches
	Shape of blade	pentagonal
	Base descriptors	pentagonal
	Leaf margin	doubly serrate
	Leaf apex	acute
	Blistering of upper side of blade	absent or very sparse
	Depth of upper lateral sinuses	shallow
	Number of lobes (Only varieties with lobed leaves)	three
55	Arrangement of lobes of upper lateral sinuses	closed
	Arrangement of lobes of petiole sinus	wide open
	Length of teeth	0.6 inches
	Ratio length/width of teeth	large
	Shape of teeth	both sides convex
	Density of prostrate hairs between main veins on lower side of blade	absent or very sparse
60	Density of erect hairs on main veins on lower side of blade	absent or very sparse

-continued

MATURE LEAF CHARACTERISTICS:		PEDICEL CHARACTERISTICS:	
Density of erect hairs between the main veins on upper side of blade	absent or very sparse	5	Length Diameter Color Pedicel texture
Density of prostrate hairs on main veins on upper side of blade	absent or very sparse		0.6 inches 0.1 inches yellow green 145A rough
Length of petiole compared to length of middle vein	equal		
Top side color		WOODY SHOOT CHARACTERISTICS:	
Bottom side color	green 137B	10	Woody shoot texture Woody shoot color Woody shoot length Diameter Internode length
Texture of upper side of blade	yellow green 147B		smooth greyed orange 165B 72 inches 0.4 inches 3.5 inches
Texture of lower side of blade	rough		
Vein color on upper blade	rough		
Vein color on lower blade	yellow green 145A	15	
Venetion pattern for upper blade	yellow green 145C		
Venetion pattern for lower blade	netlike venation		
Petiole length	netlike venation		
Petiole diameter	5 inches		
Petiole color	0.1 inches		
Petiole texture	yellow green 144B		
	rough		
Date of beginning of berry ripening in Bakersfield Calif.:		Market use of observed plants: Fresh market.	
July 4 th .		Age and growing conditions: Six years growing under Y system in South Joaquin Valley (hot, dry summers).	
BUNCH CHARACTERISTICS:		20 Shipping characteristics: Fruit was in cold storage. Stored in poly bags inside Styrofoam boxes with sulfur pads. After 30 Days: rachises were 10% green; 2% berry shattering; no berry wrinkling or cracks were apparent.	
Size (peduncle excluded)	large	DNA profile: To further the characterize the new variety DNA was extracted from plant samples and a DNA profile was obtained at California Seed & Plant Lab, California USA using base pairs for 10 standard microsatellite DNA markers. The data is presented hereafter.	
Density of berries on bunch	lax		
Bunch length	8 inches		
Bunch diameter	6 inches		
Length of peduncle of primary bunch	2.4 inches		
Diameter of peduncle of primary bunch	0.15 inches		
Peduncle of primary bunch color	yellow green 145B		
Peduncle texture	smooth		
Bunches per vine	40		
Average bunch weight	1.2 lbs		
BERRY CHARACTERISTICS:		30 TABLE 2	
Size	medium	DNA profile for ARDTHIRTYFIVE	
Length	1 inch		
Weight	0.3 oz	Microsatellite DNA Marker	Allele Sizes in Base Pairs
Diameter	0.8 inches	M1	228 234
Shape	broad ellipsoid	M2	249 249
Color of skin (without bloom)	greyed red 180A	M3	179 194
Flesh color	greyed green 193D	M4	212 216
Brix	19	M5	273 273
Titratable acidity percentage	3.9%	M6	145 151
Juice	3.6 ph	M7	187 205
Ease of detachment from pedicel	moderately easy	M8	247 255
Thickness of skin	medium	M9	214 214
Anthocyanin coloration of flesh	none	M10	247 247
Firmness of flesh	very firm		
Particular flavor	natural, sweet		
Formation of seeds	rudimentary		
Berries per bunch	106		

45 The ARDTHIRTYFIVE variety has not been observed under all possible environmental conditions to date. Accordingly, it is possible that the phenotypic expression may vary somewhat with changes in light intensity and duration, cultural practices, and other environmental conditions.

50 Additional information relating to plant and fruit disease and pest resistance or susceptibility has not been observed to date. Specification of the plant hardiness zone and the heat/cold resistance has not been observed to date.

55 What is claimed is:

1. A new and distinct grapevine, botanically known as *Vitis vinifera*, identified as 'ARDTHIRTYFIVE', substantially as shown and described herein.
